MUFFLER

Lucien L. Haas, Youngstown, Ohio, assignor to
MacKenzie Muffler Company, Inc., Youngs-
town, Ohio

Application August 31, 1939, Serial No. 292,885

6 Claims. (CL 181—61)

This invention relates to improvements in mufflers or silencers of the kind commonly employed for reducing the noise of the exhaust of internal combustion engines.

It is known that mufflers of various kinds as heretofore commonly employed become less effective in silencing sounds, if dirt, soot, or the like accumulates in the muffler and obstructs some of the openings or passages therein. Such accumulation of carbon deposits is, for example, quite pronounced in the case with mufflers used on Diesel engines, in which the exhaust contains considerable quantities of soot or unburnt carbon.

One of the objects of this invention is to provide a muffler of improved construction, which can readily be taken apart to render the interior thereof accessible for cleaning and inspection. Another object of this invention is to provide a muffler of this kind which is so constructed that the parts of the muffler are secured together in groups or units, so that when the muffler is taken apart, the individual parts of each group or unit will remain assembled in their operative positions.

A further object is to provide a muffler having a head which is constructed of two parts, one of which is secured to the outer housing of the muffler, and the other of which is detachably secured to the muffler to permit removal of the same to afford access to the interior of the muffler. A further object is to provide a muffler of this kind in which an inner muffler shell is secured to the removable part of the head for removing the inner shell from the muffler.

Other objects of this invention will appear from the following description and claims.

In the accompanying drawings:

Fig. 1 is a longitudinal central sectional view of a muffler embodying this invention, showing the parts of the muffler in their assembled or operative relation to each other.

Fig. 2 is a fragmentary central sectional view of the same muffler with the two units thereof partly separated.

Fig. 3 is a transverse sectional elevation thereof, on line 3—3, Fig. 1, and on an enlarged scale.

Fig. 4 is a fragmentary transverse sectional elevation of an interlocking arrangement for the two parts or units of the muffler, the parts being shown in their unlocked positions.

Fig. 5 is a fragmentary sectional plan view of the interlocking portion of the muffler.

Figs. 6 and 7 are respectively fragmentary sections taken on lines 6—6 and 7—7, Fig. 5.

My invention is shown in the accompanying drawings as applied to a specific type of muffler constructed and operating upon the general principles of the mufflers illustrated in the Starkweather and Haas Patent No. 2,047,442. It will be understood, however, that it is not intended to limit this invention to the particular type of muffler shown, since this invention may be used in connection with mufflers of many different types.

In the particular construction shown in the drawings, 10 represents the outer shell of the muffler and 11 an interior or inner shell arranged within the outer shell. The interior shell is provided with a plurality of groups of perforations or apertures 12 which may be of any suitable or desired shape or form. In the construction shown, the interior shell is also provided with restricting members 14 and 15 arranged between groups of perforations, and the muffler also has a baffle 16 connecting the interior and outer shells and dividing the space between these shells into two sound deadening chambers. The baffle 16 in the construction shown is welded or otherwise rigidly secured at its outer periphery to the inner face of the outer shell 10 and forms a support for an intermediate portion of the interior shell, this shell shown being provided with an annular outwardly extending bead or ridge 17 which slidably engages with an inner flange 18 of the baffle 16 when the interior shell is in its operative position.

In order to make it possible to conveniently remove the interior shell lengthwise from the muffler, I provide one of the heads of the muffler with an inner part removably secured to an outer or peripheral part of the head, the inner part of the head being of such size that when removed from the outer part, it uncovers an opening in the head of sufficient size to permit the interior shell or conduit to be moved lengthwise through the same. In the particular construction shown, the inlet head of the muffler is provided with an outer or peripheral part 20 which is welded or otherwise rigidly secured to the outer shell 10. The head also includes an inner part 21 which may be removably secured to the outer part 20 of the head in any suitable manner. The inner part of the head may be provided with the usual tubular slotted connecting portion 22 to which the exhaust pipe of an engine (not shown) may be connected in any suitable or usual manner.

The parts of my improved muffler are assembled in two units which are separable from each

other. One of these units comprises the outer shell, one of the heads of the muffler and the outer or peripheral part of the other head, together with any additional parts that may be secured to this unit, as for example the baffle 16. The other unit comprises the interior shell, with any parts that may be mounted thereon, together with the inner part of the other muffler head. Interfitting connections are provided on the two units which hold the units in their operative positions relatively to each other when assembled, and any suitable interlocking connection may be provided for holding the two units in assembled relation, for example, the two head parts 20 and 21 may be provided with an interlocking connection for this purpose, which may, for example, be constructed as follows:

The outer part 20 of the head is of annular form and is provided at its inner portion with a tubular projection 24, and the inner part 21 of the head is provided with a corresponding tubular portion 25 which may telescopically engage with the tubular projection 24. Any suitable means may be employed for securely but releasably connecting these telescoping portions of the two parts of the head, and in the construction shown for this purpose, the tubular portion 25 of the inner part of the head is provided with one or more longitudinal slits, two relatively narrow slits 27 being shown in the construction illustrated, see particularly Fig. 3 and a relatively wide slit 28. The tubular projection 24 of the outer part 20 of the head is provided on its outer surface with a suitable knob or projection 30 and the tubular portion 25 of the other part of the head is provided at a side of the larger slit 28 with a notch or recess 31 which is so formed as to receive the knob or projection 30. It will be obvious that when the inner part of the head is moved into a telescoping engagement with the outer part, the tubular portion 25 of the inner part of the head is so positioned relatively to the cooperating tubular projection 24 that the knob or projection 30 may pass into the slit 28, and upon turning the inner part 21 of the head to a slight extent, the knob 30 will pass into the recess 31, as shown in Figs. 3, 5, 6 and 7, so that endwise movement of the two parts of the head is prevented.

Suitable means are also provided for releasably clamping the two telescoping parts of the head together. In the construction shown for this purpose, a clamping band 35 is provided for this purpose, the ends of which may be drawn together by means of a bolt 36 and a nut 37 passing through suitable apertures in the outwardly turned ends of the clamping band 35. These ends are preferably spaced apart sufficiently to permit the recess 31 to be positioned between the ends of the clamping band. Any other means for releasably securing the two parts of the head together may be employed.

The inner part 21 of the head of the muffler is provided with means for supporting one end of the interior shell 11 of the muffler. In the particular construction shown for this purpose, a substantially frusto-conical connecting sleeve 40 is provided, one end of which may be welded or otherwise secured to the inner part 21 of the head, for example, to the split tubular portion 25. The inner end of the supporting sleeve 40 may support the adjacent end of the interior conduit in any suitable or desired manner, and if desired, this end of the interior shell may be welded or otherwise rigidly secured to the sup-

porting sleeve 40, for example, as indicated at 41.

The other or discharge head of the muffler may be of any suitable or desired construction, and as illustrated, the discharge head is similar in construction to the intake head which has already been described. The discharge head also includes an outer or peripheral part 20 secured to the outer shell 10 and an inner part 21, that shown being releasably secured to the outer part 20, by means of a clamp band 35 cooperating with telescoping tubular parts 24 and 25. The inner part 21 of this muffler head has a slotted tubular part 43 to which the usual tail pipe (not shown) may be secured.

15 The discharge head of the muffler is provided with a substantially frusto-conical connecting sleeve 45 which is secured to the inner part 21 of this muffler head, and which is provided at its inner end with a substantially cylindrical flange 46 preferably terminating at its inner end in an outwardly flaring portion or bell-mouth 47. This flange 46 is so formed as to provide a sliding support for the adjacent end of the interior conduit or shell 11.

20 15 When it is desired to remove the interior shell from the muffler, the clamp band 35 is loosened or removed from engagement with the slotted tubular portion 25 of the inner part of the intake head of the muffler. The inner part of this head can then be turned so that the knob or projection 30 lies in the slit 28, whereupon this part of the head can be removed lengthwise from the other part 20 of the head. If the interior conduit 11 of the muffler is secured to the sleeve 40,

30 20 then the interior shell will be moved outwardly with the inner part of the head as indicated in Fig. 2. If the welding indicated at 41 is omitted, then the interior shell 11 may be removed from the muffler separately from the inner head part 20. The interior shell, as well as the interior of the outer shell, may then be cleaned and can be replaced into the outer shell, the bell-mouth portion 47 helping to guide the adjacent end of the interior shell 11 into operative relation to the

35 25 supporting sleeve 45. The sliding connection of the interior shell with the baffle 16 and the sleeve 46 also has the advantage that the interior shell may expand and contract independently of the outer shell.

40 30 The construction described has the advantage that if the interior shell 11 is welded or otherwise secured to the inner part 21 of one of the heads of the muffler, the several parts of the muffler, with the exception of the clamp band 35 are all assembled into two units, so that the muffler can be easily taken apart and put together again. Furthermore, the muffler constructed as described has approximately the same resistance to damage by internal explosions as mufflers as heretofore made, since the pressures due to explosions are resisted mainly by the outer shell of the muffler and the outer parts 20 of the heads, which are rigidly secured to the outer shell as has heretofore been customary. Very little of the pressure resulting from the internal explosion will act on the removable inner parts 21 of the heads.

45 35 I claim as my invention:

50 40 1. A muffler including a pair of shells arranged one within another, heads permanently secured to the opposite ends of the outer of said shells, one of said heads having an opening therein of larger diameter than the interior shell, an inner head part having one end of the interior shell 55 45 secured thereto, means for removably securing

said inner head part to said last mentioned head about the opening therein, when said interior shell is positioned within said outer shell, and means fixed in said muffler for slidably supporting said interior shell adjacent to the other end thereof, whereby when said inner head part is detached from its head, it may be removed with said interior shell from said muffler.

2. A muffler in accordance with claim 1, characterized in that said head with the opening therein and said inner head part have telescopic portions for releasably securing said parts of said head together.

3. A muffler in accordance with claim 1, characterized in that the slidable supporting means for the other end of the interior shell is secured to the other head of the muffler.

4. A muffler including a pair of shells arranged one within another, heads permanently secured to the opposite ends of the outer of said shells, one of said heads having an opening therein of larger diameter than the interior shell, an inner head part having one end of the interior shell secured thereto, telescoping tubular parts formed on said head about the opening therein and on said inner head part, a projection on one of said telescopic parts adapted to extend into a recess in the other telescoping part, and a clamping band for securing said telescopic parts in operative relation to each other and for preventing said projection from moving out of engagement with said recess.

5. A muffler having the parts thereof secured to either of two units which are separable from

each other, one of said units comprising a muffler shell, and heads permanently secured to the opposite ends thereof, the other unit comprising an interior muffler shell and an inner head part secured to one end thereof, one of said heads having an opening therein of sufficient size to permit the interior shell to be inserted into and removed from the muffler lengthwise therethrough, and cooperating parts on said head and said inner head part for releasably securing said units in their operative positions with said interior shell arranged within said outer shell, and means on said first unit for releasably supporting the other end of the interior shell.

6. A muffler having the parts thereof secured to either of two units which are separable from each other, one of said units comprising a muffler shell, and heads permanently secured to the opposite ends thereof, the other unit comprising an interior muffler shell and an inner head part secured to one end thereof, one of said heads having an opening therein of sufficient size to permit the interior shell to be inserted into and removed from the muffler lengthwise therethrough, and cooperating parts on said head and said inner head part for releasably securing said units in their operative positions with said interior shell arranged within said outer shell, said first muffler unit being provided in the interior thereof with a bell-mouthed supporting device for said interior shell, whereby said interior shell may be readily inserted in its operative position in the muffler.

LUCIEN L. HAAS.
